UNITED STATES PATENT OFFICE.

MONROE STEWART, OF SAN BERNARDINO, CALIFORNIA.

GOLD-SEPARATOR.

SPECIFICATION forming part of Letters Patent No. 512,918, dated January 16, 1894.

Application filed July 18, 1893. Serial No. 480,819. (No model.)

To all whom it may concern:

Be it known that I, MONROE STEWART, a citizen of the United States, residing at San Bernardino, in the county of San Bernardino and State of California, have invented certain new and useful Improvements in Gold-Separators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in that class of gold separators in which the separation is effected by mechanical agitation assisted by the action of a current of air, or those devices known as dry separators, and 20 it consists of certain details of construction and combination and arrangement of parts more fully described hereinafter and fully embodied in the claim.

The object of my invention is to so employ 25 a current of air adapted to operate in conjunction with a series of sieves and thereby separate the earth and gold dust, that the gold will be more effectively separated and little or none of it blown out of the machine or in 30 any way wasted.

Referring to the accompanying drawings Figure 1 represents a side elevation of my invention complete, Fig. 2 a rear elevation, Fig. 3 a longitudinal section, and Fig. 4 a cross 35 section.

The reference letter A, indicates the frame of my machine which is preferably of wood and composed of six vertical beams connected at or near their upper and lower ends respectively to horizontal head beams and horizontal base beams; the whole being securely put together. Arranged at the upper end of four of the vertical beams of the frame A, two on each side, is the feed hopper A' which is 40 provided at its mouth with a forward extending chute A² and the flow of earth and gold is regulated by a gate A³ arranged on the interior of the hopper and movable toward and from the opening therein. The sieve frame 45 consists of two parallel side boards a, provided at their upper edges with the outward and laterally extending flanges a' which rest upon

the longitudinal bars a² secured to the frame A, and extending parallel to the sieve frame a, and its flanges a'. By this means the sieve 55 frame is supported in position and rendered capable of longitudinal reciprocation; and said frame being guided and steadied by the additional bars a³ arranged one on either side just below the bars a². Located in the sieve 60 frame and inclined slightly forward are the sieves B, preferably three in number and decreasing in size of mesh as they extend down for example; so that if the top sieve will have a half inch mesh the sieve below will have a 65 quarter inch mesh and the last or bottom sieve will have an eighth inch mesh. The dirt and gold on the sieves are prevented from gravitation off the lower ends thereof by means of the upwardly projecting strips of 70 tin or other sheet metal B' which extends across the lower ends.

The sieve frame a, and its attached sieves are supported to swing longitudinally by means of the links b, which are four in number, two for each end and supported by the transverse rods b', which are in turn secured two to the frame A, and two to the sieve frame. The sieve frame is so located with respect to the feed hopper A' and chute A² 80 that the latter will feed the contents of the hopper directly on the top sieve. The sieve frame is cut away at its bottom parallel with the bottom sieve and provided at its lower forward end with a sheet metal chute b² which 85 slants down and backwardly and is adapted to empty on the riffle-board C, arranged below it.

The riffle-board, C, is located just below the bottom of the sieve frame and parallel with 90 the bottom sieve and it is supported by the boxing or case C' which is of the same size as the sieve frame and is arranged directly beneath the same, with its upper edge slanting forward parallel with the lower edge of 95 the sieve frame. This box, C', is closed at its rear end and open at the front, through which front end the riffle-board is inserted so that it can be removed at will and the riffle-board is secured therein by means of the 100 wedge keys C² adapted to fit between the upper side of the board and the inwardly projecting flanges C⁴ of the box C'. The riffle board is supported in its inclined position by

means of the forwardly inclined tracks or rails C^5 which are secured in the bottom portion of the box C' and parallel with its sides. The riffle board consists of a pair of side bars 5 c , connected to each other by means of the cross bars c' and these cross bars, c' , have fixed to them and extending the entire length of the board the sections of sieves c^2 , which are secured at one end to the upper side of 10 one bar and at the other to the lower side of the adjacent bar, thus providing the under side of the board with a series of depressions or pockets which serve to more effectually catch the air blast from the bellows. 15 Arranged over the upper side of the sieve bottom of the riffle-board is a sheet of canvas or other strong cotton cloth c^3 which is made to conform to the shape of the sieves c^2 and is firmly held in place by amalgamated copper bars c^4 arranged on the top and rear side of the bars c' and securely bolted or nailed thereon. By this construction pockets are also formed on the top side of the board C , and are necessarily disposed in a direction opposite 20 to that of those in the under side. These pockets serve to catch and retain the particles of gold separated from the earth and ore; while the fine gold dust is caught and retained by the amalgamated bars c^4 from 25 whence it is removed as will fully appear hereinafter.

The reference letter D , indicates the blower or bellows by which the air blast for assisting the separation is produced. This is very similar 30 to the ordinary bellows and consists of the swinging section D' hinged to the forward end of the frame A , and provided with a flap valve D^2 seating downwardly whereby the air is admitted into the chamber of the bellows 35 but prevented from receding therethrough. Securely fastened to the edges of the swinging section D' and to the stationary top section of the bellows are the leather sides D^3 which are so arranged as to form the air tight 40 chamber essential to all bellows and by reason of its flexibility the section D' is free to swing on its hinge, thereby producing the blast. 45

Formed in the stationary or top section of 50 the bellows is a rectangular opening D^5 which is of a size nearly equal to that of the riffle-board C , through which the air blast from the bellows passes to the riffle board.

Located directly over the opening so as to 55 completely cover the same is the valved apron d , arranged to be capable of sliding longitudinally in the grooved way d' formed by the bottom of the box C' and the lower edge of the incline riffle-board supporting rods C^6 . This 60 apron consists of a body portion d , formed preferably of wood and having therein the slots or openings d^2 extending at right angles to the longitudinal disposition of the machine. Over these slats the flap valves or caps d^3 are arranged which are hinged on a line parallel with the slots d^2 by means of flexible strips of leather 65 d^4 . By this construction the air from the bel-

lows D , is allowed to pass through the apron and act on the riffle board, while any back flow of air is prevented by reason of the valve d^3 . The 70 strength of the air blast from the bellows is regulated by means of a valve D^6 arranged on the interior of the swinging section D' and adapted to command the opening D^7 therein; a stud or pin D^8 being fixed to the valve and 75 projecting through the opening D^2 to the other side of the section where it may be readily reached in order to adjust it. It will be apparent that by opening or closing this valve the air will be allowed to escape from or be 80 confined in the bellows chamber and thus made to flow through the opening D^5 in great or small quantities.

The mechanism for operating my machine will now be described. 85

The reference letter E , indicates a continuously revolving shaft journaled in bearings E' on the frame A , and having one end projecting beyond its bearing, to which end is fixed the spur gear E^2 provided with an operating crank E^3 by which motion is communicated to the shaft. Journaled just below the shaft E , and on a line therewith is a second revolving shaft E^4 , which has fixed to the end under the gear E^2 a pinion E^5 which is adapted to mesh with the spur gear and derive its motion therefrom; while the remaining end of the shaft E^4 has fixed to it, beyond its bearings, the balance wheel E^6 . Formed midway 90 the shaft E^4 is a double crank e , to the wrist pin of which is connected the vertically extending pitman e' . This pitman extends downward to a point on the same plane with the swinging section D' of the bellows D , to which section it is pivotally connected by 95 means of the arms e^2 extending out therefrom. Pivotally connected to the middle of the pitman e' is one end of an arm or link e^3 which is similarly connected at its remaining end to the lever e^4 . This lever is fulcrumed to 100 the box C' at e^5 and has the end of its upper arm pivotally connected to the sieve-frame a . By these means motion is communicated from the shaft E^4 to the section D' of the bellows and to the sieve frame a , which results in a 105 vertical, swinging motion of the former and a longitudinal reciprocating motion of the latter. 110

Handle-bars F , are provided and secured to the frame A , of the machine whereby it may 115 be easily moved to various positions.

The preferred construction of my invention having now been set forth I will proceed to describe its use and mode of operation.

After the ore has been concentrated or pulverized it is placed in the hopper A' and fed upon the sieve by way of the gate A^3 and chute A^2 . Owing to the shaking motion of the sieves the fine particles of gold and ore are sifted down onto the chute b^2 from whence 120 they are fed to the riffle board C . Simultaneously with this operation the bellows D is operating to throw a blast of air through the apron d , and riffle board C . This tends to 125 130

blow off the riffle board all particles of earth and ore that may have been small enough to pass the sieves, while the gold being much heavier than the earth will remain in the 5 pockets on the upper surface of the board provided therefor and the fine gold dust will be caught and retained by the amalgamated copper bars c^4 of the riffle board which are provided for that purpose. When enough of 10 the gold has been separated from the earth and ore to make it profitable the keys C^2 are withdrawn and the riffle board and its contents may be removed. After the gold has been collected from the riffle board the parts 15 are again placed in position and the operation repeated.

Having thus described my invention, what I claim as new, and desire to secure by Letters Patent, is—

20 A dry separator comprising the combina-

tion of a sieve capable of a reciprocal movement, a bellows adapted to direct a blast of air upon the screen, a drive shaft having a double crank thereon, a pitman connected to the crank and to the bellows whereby it is operated, a lever fulcrumed in the frame of the machine, a link connected at one end to the pitman and at the remaining end to the lever whereby the lever is rocked on its fulcrum and a second link connected to the remaining end of the lever and to the screen, whereby the screen is reciprocated in unison with the operations of the bellows, substantially as described. 25 30

In testimony whereof I affix my signature in presence of two witnesses.

MONROE STEWART.
